CLAIM

The ornamental design for electrical stimulation paddle lead, as shown and described.

DESCRIPTION

FIG. 1 illustrates a top view;

FIG. 2 illustrates a bottom view;

FIG. 3 illustrates a right end view; and,

FIG. 4 illustrates a left end view.

Although references to the drawings have been made with respect to top, bottom, right and left, it shall be appreciated that the forgoing orientations are used for reference purposes only and the model of the present invention may be disposed in any orientation.

The broken lines shown are included for the purpose of illustrating portions of the electrical stimulation paddle lead that form no part of the claimed design.
